UNITED STATES PATENT OFFICE.

CHARLES R. KLINE, OF READING, PENNSYLVANIA.

FURNACE INSULATION.

1,319,096.

Specification of Letters Patent.

Patented Oct. 21, 1919.

Application filed February 26, 1919. Serial No. 279,453.

To all whom it may concern:

Be it known that I, CHARLES R. KLINE, a citizen of the United States, residing at Reading, in the county of Berks and State 5 of Pennsylvania, have invented certain new and useful Improvements in Furnace Insulations, of which the following is a specification.

My invention relates particularly to house-10 heating furnaces, and it consists in providing improved insulating means therefor adapted to conserve fuel by preventing the waste of heat which ordinarily occurs through conduction and useless radiation by 15 the apertures necessarily employed; as fully described in connection with the accompanying drawing and specifically pointed out in the claim.

Figure 1 is a side elevation of an ordinary 20 house-heating furnace embodying my improved construction.

Fig. 2 is a sectional detail of a portion of the front wall of the furnace showing the insulation of the hinged door openings.

The drawing illustrates my invention applied to an ordinary coal-fuel steam or hot water heater comprising the usual ash-pit portion 5, exterior casing 6, fire-pot 7, and smoke outlet 8, with fuel apertures 9 and 30 cleaning aperture 10 extending through the front casing; the improvements relating solely to the insulated closure construction provided for the casing apertures in communication with the inclosed heat chamber 35 of the furnace.

Referring particularly to the fire door closure as best indicated in cross-section in Fig. 2, the casing aperture 9 communicating with the fire-pot 7, is formed with a sur-40 rounding integrally formed exterior flange 15, against which the usual insulating covering 16 of the furnace abuts; said insulating covering, as shown, extending somewhat beyond the edge of flange 15 so as to form a 45 contact seat 17 for the fire door 18. This door comprises a casting of ordinary general form having the usual hinging connection to the furnace casing. In my improved construction it is provided with an interior 50 lining 20 of insulating material; which lining is preferably a solidly formed block of such material, having a retaining bolt or bolts 21 in the body thereof extending through the metal wall of the door to rigidly 55 unite the same with the latter. This insulating lining, as shown, is extended at its

margin beyond the metal portion of the door, so as to provide an insulating seating surface 23 adapted to tightly contact with the seat 17 formed around the casing aperture 9, when the door is closed. The retaining bolt or bolts 21 are preferably embedded in the insulating lining material 20 as indicated.

The purpose and effect of this construction is to provide a closure for the aperture which will in the first place, prevent the taking up of heat by the metal portion of the door from the hot gases that are constantly in direct contact with its inner face; 65 and in the second place, prevent indirect heating thereof by conduction from the necessarily heated metal casing 6; thus avoiding all waste due to the usual radiation from the considerable exterior surface of the metal 70 door portion, and keeping the door practically cool for convenient handling.

My invention is particularly shown in connection with the fire door of a furnace, but may be applied in like manner to the 80 closures of other casing apertures communicating with the heat chamber of the furnace, and which ordinarily wastefully radiate considerable heat directly or indirectly conveyed to them because of the conductivity 85 of their metallic structure; as for instance the cleaning doors ordinarily employed, as indicated at 30, which may be readily protected in substantially the same manner as has been described in connection with the 90 fire-door closure. In connection with the usual rear aperture 8 through the casing, for the passage of the products of combustion to the smoke pipe and flue, I employ a 95 separately formed valved connecting box 35 which is insulatedly secured to the furnace casing by interposing a suitably formed seating washer 36 of insulating material between the abutting faces of the aperture casing and box respectively; and I provide the damper 100 valve 37 in said box with an insulated facing or facings 38; and also provide the slide-way formed in the wall of said box for said damper valve, as indicated, with an insulating lining 39; so as to avoid all wasteful radiation of heat.

It will be seen that with my improved insulation of the necessary outlets from the heat chambers of the furnace, the waste due to direct and indirect radiation of heat is 110 most effectively reduced to a minimum, conserving the heat within the fire box and in-

creasing the efficiency of the furnace with a considerable saving of fuel consumption.

What I claim is:—

In a heating furnace, a metallic casing having an aperture communicating with a heat chamber of the furnace and bounded by an exteriorly projecting casing flange, an insulating covering for said casing forming a closure seat around said aperture in a

plane beyond said projecting flange, and a 10 metallic closure for said aperture hinged to said casing and having an insulating covering the interior face of which is arranged to close against the insulating material forming said closure seat of the casing. 15

In testimony whereof I affix my signature.

CHARLES R. KLINE.
